ROLLING OF RECTANGULAR BARS

Joseph Scholl, Portsmouth, Ohio

Application September 29, 1933, Serial No. 691,472

11 Claims. (Cl. 80—59)

This invention relates to the rolling of rectangular bars and provides a method and apparatus whereby such bars may be rolled at low cost with great accuracy and with a resulting superior product. The word "bar" is used herein as one of general definition and not of limitation. Specifically it is not intended by the use of such term to limit its application to those bodies commercially classified in the trade as bars.

In the rolling of rectangular bodies by methods heretofore in use, the practice has been to roll in diamond passes so proportioned that the long dimension of a diamond entering a pass is reduced to the shorter dimension of the issuing diamond, there being sufficient width in the pass to permit of the entering bar spreading as it is reduced on the long dimension. Some rectangular shapes have also been rolled by a slabbing operation, but in each case the general rule has been that the metal can be reduced in only one dimension at a time. It has been considered impossible to reduce in both dimensions, that is to say, both vertically and horizontally as the piece is positioned in the rolls; first, because it was deemed impossible to enter the bar in the rolls, and second, because of the danger of overfills.

I have found that these difficulties can be overcome and a highly satisfactory product may be obtained by a material departure from accepted rules of roll design for this class of product. Briefly stated, I provide for forming a bar of generally rectangular shape but having diagonally opposite corners blunted, feeding such bar between a pair of rolls having grooves therein which form a pass of generally rectangular section smaller in both cross sectional directions than the bar and with its several main faces inclined to the roll axes. The bar is fed to this pass with its main faces inclined to the horizontal. The blunt corners permit of the bar being fed between the shoulders of the roll grooves which would be impossible if the bar were a full rectangle in cross section. The blunt corners also permit of the bar being reduced in both directions in the pass without overfilling. To obtain the full benefits of my invention I prefer that there shall be a succession of passes of the character just described and that these several passes, with the exception of the finishing pass, shall act not only to reduce the bar in both directions but also to blunt diagonally opposite corners thereof so that it will be suitable for entering the succeeding pass.

Bars made according to my invention are accurate as to size and shape and exhibit superior physical qualities. A uniform macro-structure is

obtained, micro-etchings indicate a more uniform grain size throughout, and torsion and upsetting tests show that bars rolled according to my invention are less susceptible to cracking under severe working. The several tests indicate that the metal is more uniformly worked throughout and a more homogeneous bar is obtained.

In the accompanying drawings illustrating a present preferred embodiment of the invention,

Figure 1 is a front elevation of a pair of rolls showing the manner of forming the grooves therein;

Figures 2 to 7 inclusive are views showing the successive passes and the reductions effected in each pass;

Figure 8 is a perspective of the billet employed; and

Figure 9 is a perspective view.

Figure 1 shows the general configuration of the rolls. It illustrates to reduced scale two passes each corresponding to the pass of Figure 5 hereinafter described in more detail. It will be understood, of course, that the passes might be placed in a single pair of rolls although it is preferred to use a continuous mill, successive passes being provided in successive stands, and the passes in any one stand being duplicated as many times as desired so as to reduce the number of roll changes.

Figure 1 shows a lower roll 2 and an upper roll 3 having grooves 4 and 5 cut therein to form the roll pass. The shoulders of the grooves are indicated at 6 and 7. As above indicated, it is necessary that the entering bar be of such size that it can be entered between the shoulders in an amount sufficient to permit of the rolls gripping the leading end so as to draw it into the pass.

Considerable pressure tending to displace the rolls axially is developed during the rolling and this is resisted by collars 8—8 and 9—9 bearing, respectively, on one another at 10 and 11.

Referring now to Figure 8, there is shown a billet of octagonal form, or it may be considered as a rectangle, having principal sides 12 with blunted corners 13 connected to the principal sides by radii 14. In the first pass the billet indicated as "B" in Figure 2 is fed to a pass of the shape illustrated in Figure 2. This pass is generally rectangular in form, the principal faces 15 and 16 being formed in the lower roll and the principal faces 17 and 18 being formed in the upper roll. The billet B is fed to the pass through guides which so orient it that its principal faces 12 lie substantially parallel with the principal faces of the pass opening, as indicated in Fig-

ure 2. It will be noted from Figure 2 that the billet must be reduced in both directions in the pass. This is accomplished by having the several faces 15, 16, 17 and 18 inclined to the axes 5 of the rolls. I have indicated at A—A on Figure 2 a line parallel to such axes.

The reduction of the billet causes elongation and also causes a certain amount of spreading in the pass. If this spreading were too great it would cause overfills by reason of the metal flowing into the spaces 19 at the parting line of the rolls. The blunted corners 13 of the billet allow sufficient room for spreading to insure that there will be no overfilling.

15 It has been stated that the grooves forming the roll passes have shoulders and that it is necessary for the entering bar to be of such size and shape that it can enter between the shoulders. The blunted corners also make this possible.

The pass of Figure 2 is provided with blunted corners 20 and 21 between the faces 15 and 16 and the faces 17 and 18 respectively. The rolling of the billet through this pass results in the formation of a bar whose shape I have indicated at B1 in dotted lines (Figure 3). The bar B1 is fed to the pass of Figure 3 with its blunted corners adjacent the spaces 22 at the parting line of the rolls. The pass of Figure 3 is generally like the pass of Figure 2 except that it is smaller in size. It is generally in the form of a rectangle having the principal faces 23 and 24 in the bottom roll connected by a fillet 25 at the corners, and the principal faces 26 and 27 in the upper roll connected by a fillet 28. The fillets 25 and 28 serve to drastically blunt the corners of the bar B1 to prepare it for the next pass. The principal faces of the pass in Figure 3 are inclined to the roll axis and the blunt corners of the bar B1 are so located during the rolling that they permit of entering the bar between the shoulders and also prevent overfilling. I have indicated by dimension lines R on Figure 3 the reduction on each face of the bar B1, and have indicated by dimension lines S the maximum permissible spreading of the bar B1 in the pass if overfilling is to be avoided. I have found that the distance S must be at least half the distance R if overfilling is to be avoided. This rule may be safely followed in designing passes for the rolling of bars according to my invention. The rolling of the bar B1 in the pass of Figure 3 gives a bar B2 which is rolled in the pass of Figure 4. The successive use of the passes illustrated in Figures 4 to 6 results in the successive production of bars

ing and spreading in the pass.
65 While I have illustrated and described the present preferred form of my invention, it is to be understood that the invention may be otherwise embodied and practiced within the scope of the following claims.

I claim;

70 1. In combination, a roll pass of such shape as to form by rolling a bar of generally rectangular shape but having diagonally opposite corners blunted, and a second roll pass adapted to receive and reduce a bar formed in the first-mentioned roll pass, the second pass being formed in

a pair of rolls, the pass being of generally rectangular section, smaller in both cross-sectional directions normal to its principal faces than the first pass but having a diagonal longer than the blunted diagonal of the first pass, and with its several principal faces inclined to the roll axes, the first pass being effective for blunting the corners of the bar sufficiently to permit of entering the bar between the shoulders of the roll grooves forming the second pass. 5 10

2. In combination, a plurality of roll passes each of generally rectangular cross section and diminishing progressively in size so that each roll pass is smaller in both cross-sectional directions than its predecessor, the principal faces of the 15 several rectangular passes being inclined to the axes of the rolls in which they are formed, the several passes being also so formed as to blunt diagonally opposite corners of a bar fed therethrough in an amount sufficient to permit of 20 entering such bar between the shoulders of the grooves forming the succeeding pass, the blunting being in such amount that when a piece formed in one pass is entered in the succeeding 25 pass the distance from such piece to the junction of the parting line of the rolls with the pass opening is at least half the reduction per side of the piece.

3. A rolling mill comprising successive roll passes each of generally rectangular cross sectional shape with two opposite corners blunted, the cross sectional areas of the successive passes becoming smaller toward the delivery end of the mill, at least certain of the passes each having a diagonal longer than the diagonal between the blunted corners of the immediately preceding pass. 30 35

4. A rolling mill comprising successive roll passes each of generally polygonal cross sectional shape with at least two non-adjacent corners blunted, the cross sectional areas of the successive passes becoming smaller toward the delivery end of the mill, at least certain of the passes each having a diagonal longer than a diagonal through a blunted corner of the immediately preceding pass.

5. A rolling mill comprising successive roll passes each of generally polygonal cross sectional shape with at least one corner blunted, the cross sectional areas of the successive passes becoming smaller toward the delivery end of the mill, at least certain of the passes each having a diagonal longer than a diagonal through said blunted corner of the immediately preceding pass. 50

6. A method of rolling products of generally rectangular cross-section, comprising reducing a blank in a roll pass to generally rectangular cross-section with a face of the blank inclined to the roll axes and with opposite corners blunted and then reducing the blank in another roll pass the roll axes of which extend at substantially the same angle to the horizontal as the roll axes of the first mentioned pass and increasing in the second mentioned pass the transverse dimension of the blank through the blunted corners formed in the first mentioned pass. 55 60 65

7. A method of rolling products of generally rectangular cross-section, comprising reducing a blank in a roll pass to generally rectangular cross-section with a face of the blank inclined to the roll axes and with opposite corners blunted and then reducing the blank in both directions parallel to its principal faces in another roll pass the roll axes of which extend at substantially the same angle to the horizontal as the roll axes 75

of the first mentioned pass and increasing in the second mentioned pass the transverse dimension of the blank through the blunted corners formed in the first mentioned pass.

- 5 8. A method of rolling products of generally rectangular cross-section, comprising reducing a blank in a roll pass to generally rectangular cross-section with a face of the blank inclined at an angle less than 45° to the roll axes and with 5
10 opposite corners blunted and then reducing the blank in another roll pass the roll axes of which extend at substantially the same angle to the horizontal as the roll axes of the first mentioned pass and increasing in the second mentioned pass
15 the transverse dimension of the blank through the blunted corners formed in the first mentioned pass.

9. A method of rolling products of generally rectangular cross-section, comprising reducing 20 a blank in a roll pass to generally rectangular cross-section with a face of the blank inclined to the roll axes and with opposite corners blunted the blunting of such corners being in such amount that the distance from the blank to the 25 junction of the parting line of the rolls with the pass opening is at least half the reduction per side of the blank, and then reducing the blank in another roll pass the roll axes of which extend at substantially the same angle to the horizon- 30 tal as the roll axes of the first mentioned pass and increasing in the second mentioned pass

the transverse dimension of the blank through the blunted corners formed in the first mentioned pass.

10. A method of rolling products of generally rectangular cross-section, comprising reducing a blank in a roll pass to generally rectangular cross-section with a face of the blank inclined to the roll axes and with opposite corners blunted and then reducing the blank in both directions parallel to its principal faces in another roll pass 10 the roll axes of which extend at substantially the same angle to the horizontal as the roll axes of the first mentioned pass and with the opposite corners intermediate those blunted in the first mentioned pass blunted and increasing in the 15 second mentioned pass the transverse dimension of the blank through the blunted corners formed in the first mentioned pass, the blunting of the corners being in such amount that the distance from the blank to the junction of the parting line 20 of the rolls with the pass opening is at least half the reduction per side of the blank.

11. A roll stand comprising rolls forming a pass the principal faces of which extend substantially at right angles to one another, said pass 25 having adjacent principal faces both inclined at an acute angle to the roll axes, said inclination being unequal as to the respective principal faces, said pass also having at least two non-adjacent corners blunted. 30
